UNITED STATES PATENT OFFICE.

MERLIN COMSTOCK, OF LOS ANGELES, CALIFORNIA.

SADDLE.

SPECIFICATION forming part of Letters Patent No. 288,026, dated November 6, 1882.

Application filed May 17, 1883. (No model.)

To all whom it may concern:

Be it known that I, MERLIN COMSTOCK, of Los Angeles, in the county of Los Angeles and State of California, have invented a new and useful Improvement in Saddles, of which the following is a full, clear, and exact description, reference being had to the annexed drawings, forming part of this specification.

This invention relates to riding-saddles; and it consists of the novel construction hereinafter described and claimed.

In the drawings, Figure 1 is a perspective view of the frame-work of a side-saddle embodying my improved saddle-tree and spring-seat. Fig. 2 is a bottom view of the spring-seat, the saddle-tree being broken away; and Fig. 3 is a partial view, showing the side-saddle converted into a man's saddle.

A indicates the saddle-tree, which is to be made of either metal or wood, preferably of wrought, cast, or malleable iron. The forward and rear ends, B, may be formed of separate bowed pieces B', flattened on top and connected together by side pieces, C; or the said pieces may be formed of one continuous piece.

To the ends of the bowed pieces, or to the corners of the tree A, are hinged a pair of pads, D, made preferably of narrow strips of spring-steel E, secured to curved cross-pieces F in such manner as to give the under side of the pads a convex surface. The pads are intended to be faced with leather or other suitable material. The cross-pieces F, by which the pads are hinged to the tree, are secured to the strips E, with intervening rubber cushions, G, in order that a great degree of flexibility shall be secured to the said strips, whereby they may be able to adjust themselves to the back of an animal. The cross-pieces at the middle of the pads will serve as extra bearings for the tree when heavily pressed.

On the flattened tops of the saddle tree, by means of suitable springs, is supported the seat H. This seat is formed by means of strips I, of spring-steel or other elastic material, which are secured to a supporting-rim, J, of a shape corresponding to the animal's back.

The strips I are arranged side by side, and have their forward ends straight, while their rear ends are curved downward and secured

to a support, K, underneath the same. I have shown the seat supported at the rear on bowed springs L, which project rearward and have their ends attached to the tree and seat, respectively, and between these ends, attached either to the seat or tree, is a rubber cushion, M, adapted to prevent the seat from being forcibly depressed against the tree. The forward end of the seat is supported on two bowed springs, N, which extend to either side, and serve also as horns for a side-saddle. A spiral spring, O, may also be arranged between the seat and tree at the forward end, and to prevent the seat from being accidentally lifted against the tension of the springs, it is connected to the tree by a strap, P. To support the seat at the sides, two pairs of spring-braces, Q, are extended from the front and rear, respectively, of the tree to points of attachment R on the sides of the seat. When the seat is to be used for a side-saddle, a curved back, S, is to be attached to the rear and front of the seat-rim by movable bolts. To the front of this back is attached a horn-piece, T, which is adapted to fit between the springs N when said springs are used, and which will serve to provide a horn when said springs are not used. The back S is also provided with a wire or cord, U, extending across from one end to the other on the inside, and resting approximately on the top of the seat. To this wire and the outer edge of the seat-back a covering for the cushion of the seat is to be attached. To one of the springs N is attached an adjustable guard or under horn, V, to be used in side-saddles.

By removing the back S and turning the springs N forward until they meet, a frame, W, carrying a horn, Y, may be placed across the forward end of the seat and secured to the tree in any detachable manner, to convert the side-saddle into a man's saddle.

I design also to make side-saddles and men's saddles separate as well as in one, and shall also construct spring-seats adapted for being attached to any ordinary saddle-tree.

While preferring the construction of the seat as above described for the best class of saddles, I may make cheaper seats by using less spring metal; or I may rely upon the supporting-springs of the seat for the elasticity

desired, making the body of the seat in any required manner.

I do not mean to limit myself to the above-described arrangement of the springs for supporting the seat, since the same general result may be accomplished with other arrangements equally as simple and convenient.

The girth and stirrup-straps are to be attached, respectively, to the tree and seat, as indicated in the drawings. The seat may also be provided with a girth for holding it steady.

It is understood that the frame of the saddle, as above described, is to be trimmed with leather or other material in the usual manner.

15 What I claim is—

1. The combination, with the spring-seat and the supporting-springs, of the improved saddle-tree having the pads formed of strips of spring-steel E, and rubber cushions G, secured to cross-pieces F, which are hinged to the tree, substantially as shown and described.

2. The combination of the seat formed of the supporting-rim J with the strips I, of spring-steel, secured thereto at their ends, and 25 having their rear ends curved under the supporting-springs and the saddle-tree, substantially as shown and described.

3. The combination, with the tree and seat, 30 of the bowed springs N, adapted to be turned either to the front or to the sides, whereby the seat may be adapted for a side-saddle or a man's saddle, as specified.

4. The combination, with the saddle-tree 35 and the seat, of the springs L N at the rear and front, and the spring-braces Q, connecting the sides of the seat at their center with the ends of the tree, substantially as shown and described.

5. The combination, with the seat, of the removable back having a horn-piece secured to its forward end, and the wire or cord extending from one end to the other and adapted to rest upon the seat, substantially as shown and 40 described.

6. The combination, with the seat and tree, of the springs N, adapted to form horns, and the removable and adjustable guard or under horn attached to one of said springs, substantially as shown and described. 50

MERLIN COMSTOCK.
